UNITED STATES PATENT OFFICE.

CHARLES H. NORTON, OF WORCESTER, MASSACHUSETTS, ASSIGNOR TO NORTON
GRINDING COMPANY, OF WORCESTER, MASSACHUSETTS, A CORPORATION OF
MASSACHUSETTS.

FOOT-STOCK SUPPORT.

1,119,030.

Specification of Letters Patent.

Patented Dec. 1, 1914.

Application filed July 22, 1914. Serial No. 852,387.

To all whom it may concern:

Be it known that I, CHARLES H. NORTON, a citizen of the United States, residing at Worcester, in the county of Worcester and State of Massachusetts, have invented a new and useful Foot-Stock Support, of which the following is a specification.

This is a division of my application for patent on a cylindrical grinding machine filed June 6, 1913, Ser. No. 772,055.

This invention relates to a foot stock support or slide, and the principal object thereof is to provide a construction in which it is practically impossible for the sliding surfaces on which the foot-stock is supported to ever wear out of line. This is accomplished by arranging the slide on which the foot-stock is directly carried to cover the entire surface of the supporting surface therefor on the grinding machine table. In this way a pair of long bearing surfaces are secured which work one upon the other, whereby the wear is distributed so broadly that no great wear can take place at any point and thus permit the slide to get out of line on that account. This is an important improvement over the usual construction in which the tail stock slides back and forth on ways, and if used very much in one position will wear the ways there and thus get them out of line.

Reference is to be had to the accompanying drawings in which—

Figure 1 is a plan of a foot stock slide and connected parts constructed in accordance with this invention and showing the centers near together; Fig. 2 is a similar view showing the position of the posts when the centers are far apart; and Fig. 3 is a transverse sectional view on the line 3—3 of Fig. 1.

The invention is shown as applied to a grinding machine having the usual sliding table B, this sliding table having thereon a plate A which is adjustable at the end to change the angle of the same with respect to the grinding wheel C. The parts for supporting the wheel are not shown herein as they constitute no part of this invention.

The plate A is also provided with an upward longitudinal projection A' having a long inclined guiding surface A² for the tail stock slide D. This slide has an inclined surface resting on the surface A² and the latter surface constitutes a V-shaped sup-

porting guide for it. The slide is provided with a downwardly extending flange D' along the upper edge and with a flange d on the other side which projects beyond the lower edge of the surface A². A clamping screw E is used to keep it in position on the guide. The plate A is shown as provided with a wide concave flange a on the front and another flange b is located on the rear of the table. These form troughs for receiving the water. The upper inclined surface of the slide which supports the steady rest has some transverse grooves a' for directing the water down into the trough a. The work F is held between the head center G and tail center H. These centers are mounted on the usual head stock I and tail stock J, the former of which is directly supported by the plate A, and movable with it. The tail stock, however, is cast integrally with the slide D and of course the tail center necessarily follows absolutely the motion of the slide and keeps its alignment on account of the construction of the slide. It is to be observed that this slide D has a length a little greater than the length of the supporting surface A² and in fact extends substantially from one end of the machine to the other. In this way its bearing is throughout its own length in all ordinary positions of the parts, and consequently its bearing points are widely separated so that not only is the wear distributed over a long surface but any wear that does take place can have only a slight effect on the relative angularity of the slide and supporting surface A². Nearly all of this supporting surface is also used in supporting the slide in most positions thereof, and consequently the same remarks apply to that.

The slide is provided with a cover plate L of a shape substantially that of the slide and projecting beyond it at the tail end of the machine for the purpose of keeping the surface A² covered in the most extreme positions of the slide. This slide is adapted for the support of the steady-rest M for engaging the work F. Thus the steady rest and tail stock move together and can be adjusted together in some cases.

Although I have illustrated and described only a single embodiment of the invention and shown it applied only to one type of grinding machine, I am well aware of the fact that it is capable of wider application

and that many modifications can be made in the details of construction without departing from the scope of the invention as expressed in the claims. Therefore I do not 5 wish to be limited in these respects, but

What I do claim is:—

1. In a grinding machine, the combination of a table for supporting the work, a plate adjustably mounted thereon and provided with a guiding surface thereon extending throughout the greater portion of the length of the table, and a foot stock slide mounted thereon and having a relatively fixed bearing surface covering the entire guiding surface, whereby the wear will be distributed throughout the length of the guiding surface and will be prevented from causing the slide to get out of line.

2. In a grinding machine, the combination with a table for supporting the work, and a plate mounted thereon and provided with a long guiding surface, of a foot stock slide mounted thereon and having a rigid bearing surface substantially as long as the entire guiding surface.

3. In a grinding machine, the combination of a plate adapted to be supported on the work table and having projecting upwardly therefrom an inclined longitudinal guiding surface, a head stock at one end of the plate, said guiding surface extending substantially from the head stock to the tail end of the plate, a slide having a wearing under surface fitting and resting on the said inclined surface and covering it substantially throughout its length, and a tail stock carried rigidly by said slide.

4. In a grinding machine, the combination of a plate adapted to be supported on the work table and having projecting upwardly therefrom an inclined guiding surface, a head stock fixed at one end of the plate, said guiding surface extending substantially from the head stock to the tail end of the plate, a slide having an inclined

wearing under surface fitting and resting on the said inclined guiding surface and covering it substantially throughout its length and provided with a flange extending down from the upper side and engaging the said 50 plate at the upper edge of its inclined surface, and a tail stock integral with the slide.

5. In a grinding machine, the combination of a plate adapted to be supported on 55 a work-table and having a longitudinal guiding surface thereon, a head-stock at one end of the plate, said guiding surface extending substantially from the head-stock to the tail end of the plate, a slide having 60 a wearing surface fitting and resting on said guiding surface and covering it throughout the major portion of the length of said guiding surface, and a tail stock carried by said slide.

6. In a grinding machine, the combination with a table for supporting the work, and a plate mounted thereon and provided with a long guiding surface, of a foot stock slide mounted thereon and having a bearing surface, a foot stock on said slide and a steady rest mounted on the slide and movable therewith.

7. In a grinding machine, the combination of a table for supporting the work, a 75 plate adjustably mounted thereon and provided with a guiding surface thereon, and a foot stock slide mounted thereon, said guiding surface and the under surface of the slide being inclined, the inclined guiding surface having transverse grooves for leading the water away, and the plate having a trough for receiving the water.

In testimony whereof I have hereunto set my hand, in the presence of two subscribing 85 witnesses.

CHARLES H. NORTON.
